DESIGN FOR A TEA-KETTLE, STAND, AND LAMP.

No. 39,119.

Specification for Design.

Patented Feb. 11, 1908.

Application filed December 3, 1907. Serial No. 404,966. Term of patent 7 years.

To all whom it may concern:

Be it known that we, SIGMUND STERNAU, a citizen of the United States, and a resident of the borough of Manhattan, city, county, and State of New York, and CHARLES NELSON, a subject of the King of Sweden, and a resident of the borough of Brooklyn, county of Kings, State of New York, have invented a new, original, and ornamental Design for a Tea-Kettle, Stand, and Lamp, of which the following is a specification, reference being had to the accompanying drawing, forming part thereof.

The figure is a perspective view of a tea-kettle, stand and lamp showing our new design.

We claim:

The ornamental design for a tea-kettle, stand and lamp, as shown.

SIGMUND STERNAU.
CHARLES NELSON.
